CLAIM

The ornamental design for a blanket, as shown and described.

DESCRIPTION

FIG. 1 is a front view of a blanket showing our new design; FIG. 2 is a front view of a blanket showing our new design of FIG. 1 with a portion in a folded configuration; FIG. 3 is a rear view of a blanket showing our new design; FIG. 4 is a right side view thereof; FIG. 5 is a left side view thereof; FIG. 6 is a top view thereof; FIG. 7 is a bottom view thereof; FIG. 8 is an enlarged view of the region identified by the number “8” in FIG. 3 thereof; and, FIG. 9 is an enlarged view of the region identified by the number “9” in FIG. 3 thereof. The even-length broken lines within the shaded area represent stitching. The uneven-length broken lines immediately adjacent to the shaded area define the bounds of the claimed design and form no part thereof. The even-length broken lines depicting the remainder of the blanket show features that form no part of the claimed design.
